Primary Examiner — Austin Murphy(74) *Attorney, Agent, or Firm* — ArentFox Schiff LLP; Michael Fainberg(57) **CLAIM**

The ornamental design for a headset base as shown and described.

DESCRIPTION

FIG. 1 is a top front right perspective view of a headset base showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top of the design shown in FIG. 1; and,

FIG. 7 is a bottom view of the design shown in FIG. 1.

The broken lines shown in the figures are included for the purpose of illustrating portions of the headset base and form no part of the claimed design.

1 Claim, 3 Drawing Sheets(56)
